Term of patent 7 years

(Cl. D19—2)

Fig. 1

Fig. 2

Fig. 3

Fig. 4

Fig. 1 is a top plan view of a casket hardware handle bracket, showing my new design;

Fig. 2 is a front elevational view;

Fig. 3 is a bottom plan view; and

Fig. 4 is an end view, the opposite end being substantially a mirror image thereof.

The broken line fragmentary showing of a handle is for illustrative purposes only.

I claim:

The ornamental design for a casket hardware handle bracket, substantially as shown and described.
